UNITED STATES PATENT OFFICE.

VICTOR C. DOERSCHUK, OF MASSENA, NEW YORK, ASSIGNOR TO ALUMINUM COMPANY OF AMERICA, OF PITTSBURGH, PENNSYLVANIA, A CORPORATION OF NEW JERSEY.

RING-FURNACE.

1,330,175.

Specification of Letters Patent. Patented Feb. 10, 1920.

Application filed May 1, 1919. Serial No. 294,120.

To all whom it may concern:

Be it known that I, VICTOR C. DOERSCHUK, a citizen of the United States, residing at Massena, in the county of St. Lawrence and State of New York, have invented certain new and useful Improvements in Ring-Furnaces, of which the following is a full, clear, and exact description.

This invention relates to so-called "ring" furnaces, for heating or baking articles of various kinds, as for example carbon electrodes for arc-lighting, for electric furnaces, for electrolytic processes, etc. In furnaces of this type as usually constructed at the present time, two parallel rows of heating chambers are constructed, preferably under ground and with the tops of the chambers flush with or extending slightly above the surface of the ground. When the furnace is in operation all the chambers are in use in such manner that one or more chambers containing articles already heated or baked (and still hot) are being cooled by air drawn in from the outside. This air, pre-heated by absorption of heat from the previously fired chambers, is delivered to the next chamber and there supports combustion of the producer gas or other fuel with which the furnace is fired. From the furnace under fire the products of combustion pass through the next section or sections, and, in doing so, give up heat to the articles therein, thereby pre-heating such articles. When the articles in the chamber or section under fire are sufficiently heated or baked the supply of fuel is diverted therefrom to the next chamber, that is, the first of the chambers in which articles are being pre-heated. At the same time cooled articles from the first of the previously fired chambers are being removed, and fresh unheated or unbaked articles are being placed in the first empty chamber beyond those containing articles which are being pre-heated. In this way the fire proceeds down one row or series of chambers, then crosses over to the adjoining row, passes up the latter row to the end, and then over to the first row again, and so on. Hence the name "ring" furnace.

The present invention relates to furnaces of this general type, and its object is to provide an improved furnace of high efficiency.

To this and other ends the invention consists in the novel features of construction

and combinations of elements hereinafter described.

Referring now to the drawings, in which a furnace embodying the present invention is illustrated,

Figure 1 is a cross-section on line 1—1 of Fig. 2.

Fig. 2 is a sectional plan view on the planes indicated approximately by the lines *a*—*a*, *b*—*b* and *c*—*c* of Fig. 1.

Fig. 3 is a longitudinal section, about on line 3—3 of Fig. 2.

Fig. 4 is a diagrammatic longitudinal section illustrating the course of air and gases through the flues of the furnace.

Fig. 5 is a detail view of a burner port and an associated air-port, to illustrate the method of regulating the size of the ports.

Fig. 6 is a similar view but showing both ports closed.

Referring now to Fig. 4, X indicates a chamber which has been opened to permit the removal of heat-treated and thoroughly cooled articles, for instance carbon electrodes, hereinafter referred to simply as "carbons." One or more succeeding chambers, for example three, indicated by *a*, *b*, *c*, contain carbons that have been baked. Outside air enters the gas passage 14 (the covers 15^a being removed) and passing into the channeled or hollow walls and partitions of chamber X flows through the similar walls, partitions and bottoms of chambers *a*, *b*, *c*, absorbing heat from these chambers and their contents and being thereby preheated, as will be readily understood. At Y gaseous fuel is introduced and is burned at the burner-ports *y*, the combustion being supported by the preheated air, from chambers *a*, *b*, *c*, issuing from air-ports *y'*. The intensely hot products of combustion pass downwardly through the channels in the hollow walls and partitions and through the channeled bottom of chamber *d*, and in like manner through the walls, partitions and bottoms of one or more succeeding chambers, for example three, indicated by *e*, *f*, *g*, passing finally to the waste-gas flue at Z. The carbons in *d* are thus baked, and the products of combustion give up heat to the unbaked carbons previously placed in chambers *e*, *f*, *g*. These unbaked carbons are thus preheated. When the carbons in *d* are sufficiently baked the supply of fuel gas is cut off at Y and switched to Y', and is ignited

105
110

at the burner-ports of chamber *e*. At the same time the gas inlet at *Y* is closed, so that the air from chamber *c* passes through the channels of chamber *d*, thereby being further heated, and unites with the gas burning in the walls and partitions of chamber *e*. In the meantime chamber *X* has been emptied and is ready for refilling; chamber *a* has been cooled sufficiently to permit the removal of its contents; and another chamber, *h*, through the rear wall of which outside air has been admitted to the next chamber and others beyond, has been loaded, so that the products of combustion from chamber *e*, now being fired, pass through the walls, partitions and bottoms of chambers *f* and *g* but also of chamber *h*, and thence to the waste-gas flue, it being understood that the connection to the flue has moved from *Z* to *Z'*. While chamber *d* was being fired, the air and burner-ports of chamber *h* were blocked by suitable closures as described hereinafter, so that the suction of the exhaust fan (not shown) connected to the waste-gas flue was exerted only on the chambers in the rear of chamber *h*. In like manner chamber *f* is next fired, the firing taking a progressive course up the first row of chambers, then across to and down the second, then across to and up the first again, and so on continuously.

In the procedure specifically outlined above (merely to illustrate and explain the general operation of the furnace), eight chambers, for instance chambers *X*, *a*, *b*, *c*, *d*, *e*, *f*, *g*, constitute what for convenience may be termed a "group." Of these the first (*X*) is being unloaded and, later, reloaded. The next three (*a*, *b*, *c*,) contain baked carbons which are being cooled by air admitted through chamber *X*. The next (*d*) is being fired, and the next three (*e*, *f*, *g*,) are being preheated by products of combustion from *d*. If, as is usually the case, there are in the entire furnace more chambers than enough for a single group, one or more other groups are in operation at the same time. Hence it is customary to make the total number of chambers an even multiple of the number in a single group. Thus with forty chambers, five groups of eight each can be operated simultaneously. It will also be observed that as the operations proceed, the make-up, so to speak, of each group changes. For instance, reverting to the illustrative example outlined above, when chamber *e* is being fired its group (which we may term group 2) comprises chambers *a*, *b*, *c*, *d*, *e*, *f*, *g*, *h*, chamber *X* having become the last chamber of the preceding group (which we may term group 1) and chamber *i* having become the first of group 3.

The chambers comprising the furnace illustrated in Figs. 1, 2 and 3 are all exactly alike save for certain modifications in the

end chambers, entailed by their positions, as will be explained hereinafter. Each chamber is divided by longitudinal intermediate walls or partitions 10 into a plurality of cells or compartments, four in the present embodiment of the invention. These partitions, the side walls 11, the end walls 12, and the bottoms or floors 13, are all hollow, providing passages, channels, or flues for the air, the gaseous fuel, and the products of combustion. Across the top of each end wall is a horizontal gas passage 14 having burner-ports *y* opening into the upper portions of the hollow partitions and side walls. The top of each gas passage is provided with openings 15, one at each partition and side wall for access to the ports immediately below to permit convenient adjustment of the blocks 16, 17, Fig. 3, and to close the ports when necessary or desirable. These openings can be closed by removable covers 15^a. When a chamber is being fired its gas passage 14 is connected to the gas main 18, extending longitudinally of the furnace between the two rows of chambers. This connection is made by means of a removable siphon-shaped connector or "elephant" 19, extending from an adjacent opening 20 in the main to one of the openings 15 in the gas passage 14. Gas is thus supplied to the latter passage and delivered to the burner-ports. When a chamber is the last of a group the ports in its rear end wall (constituting the front end wall of the next chamber) are closed by any convenient means, as explained hereinafter, and the gas passage 14 is connected to the adjacent waste-gas flue 21, Figs. 1 and 2, by means of connector or "elephant" 22, extending from an adjacent opening in the flue to one of the openings 15 in the gas passage.

In front and rear of each opening 15 are peep-holes 23, Fig. 3, provided with removable covers 24, to permit convenient inspection of the passages or channels in the side walls and partitions.

The down-flues 25 in the longitudinal partitions 10, are provided with one or more baffles, as 26, Fig. 3, and at the bottom are provided with lateral ports 27 leading into the longitudinal floor-channels 28, Figs. 3 and 1, under the compartments in which the carbons are placed for baking. These floor-channels or flues are closed at the front end but open at the rear into the up-flues 29, Fig. 3, in the adjacent end wall.

To make the best use of the space available and to afford the most rapid conduction of heat the carbons are packed as close together as possible and in contact with the bottom, sides and ends of the compartments. As the loading of a compartment progresses the interstices between the carbons are filled with carbon dust, and when a chamber is

full it may be covered in any convenient way to minimize the escape of heat. For this purpose bricks or clay slabs may be laid over the top and the whole covered 5 with earth.

A waste-gas flue, such as 21, Figs. 1 and 2, is provided at each side of the furnace, and the two flues are preferably connected across one end; at least, of the furnace. 10 Natural draft can be used to cause the air and products of combustion to flow through the various passages or channels, or fans, not shown, can be employed, or both, as desired. The fuel gas main 18 extends longitudinally of the furnace between the two rows of chambers, and is connected with a suitable source of gas, for example a producer, not shown. The rear end-wall of the last chamber of each row of chambers 15 20 is not provided with burner-ports, but its flues are connected in any suitable manner, not shown, to the up-flues in the front end-wall of the first chamber of the other row, so that the operation of the furnace can be 25 carried across from one row to the other, as will be readily understood.

It will be observed that the gas from the transverse passages 14 is discharged into and is burned in the down-flues in the longitudinal partitions and side walls, and that 30 all the passages, channels and flues are closed with respect to the cells or compartments in which the articles are being pre-heated, baked or cooled. This is a highly 35 important feature, especially when the articles being treated are made of carbon, since it eliminates the oxidation which would follow if the air, or products of combustion containing any uncombined oxygen, were 40 allowed to come in contact with the heated carbon. Another important feature is the division of the chambers into cells by means 45 of longitudinal partitions with individual burners, as it provides a better distribution of heat among the articles in the chamber, thus attaining more uniform results in baking. The area of the burner-ports and air-ports can be regulated individually by 50 proper proportioning and positioning of the tiles or brick 16, 17, Figs. 3 and 5, to insure uniform distribution of the air and gas. These tiles are simply laid on the blocks of shelves 30, 31, Fig. 5, and when the ports are to be closed they are removed through 55 the opening 15 above. The vertical tile or slab 33, Fig. 6, is then inserted to close the opening into the associated channel or flue 25 when the products of combustion are to be diverted to the waste gas flue. It is also 60 possible in this way to cut out any one or more of the compartments at will, as may be necessary or desirable in case of injury to the side walls or partitions. The connectors 19, between the gas manifold 18 and 65 the gas passages 14, may also be provided

with valves, as indicated diagrammatically at 32, Fig. 1.

It is to be understood that the invention is not limited to the details of construction herein specifically illustrated and described, 70 as these can be varied within wide limits without departure from the spirit of the invention as defined by the following claims.

I claim:—

1. In a furnace of the kind described, a 75 longitudinally extending series of chambers defined by transverse end-walls each having vertical flues and a series of burner-ports above the flues, and side-walls having flues communicating with flues in the end-walls; 80 longitudinal partitions dividing the chambers vertically into compartments and having flues communicating with the flues in the end-walls, and means for delivering fuel gas to any series of burner-ports at 85 will; said burner-ports opening directly into the flues in the side walls and partitions in the direction of the flow of air and gas through the furnace.

2. In a furnace of the kind described 90 comprising a longitudinal series of chambers having hollow walls for the flow of air or products of combustion through the same in succession, a chamber having a front end-wall provided with vertical air flues and a 95 horizontal series of burner-ports; side-walls having flues communicating with flues in the front end-wall to receive air or products of combustion therefrom; one or more vertical longitudinal partitions dividing the 100 chamber into cells or compartments for articles to be treated and having flues communicating with flues in the front end-wall to receive air or products of combustion therefrom, the burner-ports of said series 105 opening toward the rear directly into the respective flues in the side-walls and partitions; and a rear end-wall having vertical flues communicating with the flues in the side-walls and partitions to receive air or 110 products of combustion therefrom, and having a horizontal series of burner-ports opening toward the rear of the wall.

3. In a furnace of the kind described 115 comprising a longitudinal series of chambers having hollow walls for the flow of air or products of combustion through the same in succession, a chamber having a front end-wall provided with vertical flues and a transverse gas-passage; side-walls 120 having flues communicating with flues in the front end-wall to receive air or products of combustion therefrom; one or more vertical longitudinal partitions dividing the chamber into cells or compartments for articles to be treated and having flues communicating with flues in the said front end-wall to receive air or products of combustion therefrom, the said transverse gas 125 passage having burner-ports opening to 130

ward the rear directly into the respective flues in the side-walls and longitudinal partitions; a hollow floor or bottom communicating with the flues in the side-walls and 5 partitions to receive air or products of combustion therefrom; and a rear end-wall having vertical flues communicating with the hollow floor to receive air or products of combustion therefrom, and having a trans- 10 verse gas passage provided with burner-ports opening toward the rear.

4. In a furnace of the kind described comprising a longitudinal series of chambers having hollow walls for the flow of air or 15 products of combustion through the same in succession, a chamber having one or more hollow vertical partitions extending longitudinally and dividing the chamber into cells or compartments for the articles to be 20 treated; hollow side-walls; a front end-wall having vertical flues provided with ports at the top opening into the respective hollow partitions and side-walls to deliver air or products of combustion thereto, and having 25 a horizontal gas passage above the vertical flues, provided with burner-ports opening into the respective hollow side-walls and partitions; and a rear end-wall having vertical flues communicating at the 30 bottom with the respective hollow side-walls and partitions, and having a horizontal gas passage provided with burner-ports opening toward the rear of the wall.

5. In a furnace of the kind described comprising a longitudinal series of chambers having hollow walls for the flow of air or 35 products of combustion through the same in succession, a chamber having one or more vertical partitions extending longitudinally to divide the chamber into cells or compartments and having flues; side-walls having flues; a front end-wall having vertical flues opening at the top rearwardly into the flues in the respective side-walls and partitions opening at the bottom forwardly, and having a horizontal gas passage provided with burner-ports opening 40 into the flues in the respective side-walls and partitions; a hollow floor or bottom 45 communicating with the flues in the side-walls and partitions to receive air or products of combustion therefrom; and a rear end-wall having vertical flues open at the bottom to the hollow floor to receive air or 50 products of combustion therefrom and at the top having openings toward the rear, said rear end-wall having at its top a horizontal gas passage provided with burner-ports opening 55 toward the rear.

6. In a furnace of the kind described comprising a longitudinal series of chambers having hollow walls for the flow of air or 60 products of combustion through the same in succession, a chamber having hollow side-walls and one or more hollow longitudinal

partitions; a front end-wall having vertical flues open at the bottom toward the front and at the top having ports opening rearwardly into the hollow side-walls and partitions, said end-wall having above the vertical flues a horizontal gas passage provided with burner-ports opening toward the rear directly into the respective hollow side-walls and partitions; and a hollow rear end-wall having openings at its bottom communicating with the hollow side-walls and partitions. 70

7. In a furnace of the kind described comprising a longitudinal series of chambers having hollow walls for the flow of air or 80 products of combustion through the same in succession, a chamber having longitudinally extending hollow walls, a hollow end-wall having air-ports opening into the hollow longitudinal walls and having a horizontal series of burner-ports opening into the hollow longitudinal walls adjacent to the aforesaid air-ports, and means adjustable from outside for varying the size of the burner-ports. 85

8. In a furnace of the kind described comprising a longitudinal series of chambers having hollow walls for the flow of air or products of combustion through the same in succession, a chamber having hollow side-walls; hollow partitions extending longitudinally and dividing the chamber into cells or compartments for the articles to be treated; and an end-wall having a horizontal flue provided with air-ports opening into the hollow side-walls and partitions, vertical flues between the side-walls and partitions and opening at the top into said horizontal flue, and a horizontal gas passage above the horizontal flue, provided with burner-ports opening into the hollow side-walls and partitions above the aforesaid air-ports. 95 100

9. In a furnace of the kind described comprising a longitudinal series of chambers having hollow walls for the flow of air or 110 products of combustion through the same in succession, a chamber having hollow side-walls and one or more hollow longitudinal partitions; an end-wall having a horizontal gas passage at its top provided with burner-ports opening directly into the hollow side-walls and partitions and with openings in 115 its top for access to said ports, the end-wall also having vertical flues provided at the top with air-ports opening into the hollow side-walls and partitions immediately below said burner-ports; means for varying the size of the air-ports and burner-ports individually, operable through the said openings in the gas passage; and removable closures for said 120 openings. 125

10. In a furnace of the kind described comprising a longitudinal series of chambers having hollow walls for the flow of air or products of combustion through the same 130

- in succession, a chamber having two or more hollow longitudinal walls; and an end-wall having flues provided with air-ports opening into the hollow longitudinal walls, a horizontal gas passage having burner-ports adjacent to the said air-ports and opening into the hollow longitudinal walls, and peep-holes opening into the hollow longitudinal walls adjacent to the burner and air ports.
11. In a furnace of the kind described comprising a longitudinal series of chambers having hollow walls for the flow of air or products of combustion through the same in succession, a transverse end-wall having vertical flues and a horizontal gas passage,
- and hollow longitudinal walls extending in both directions from the end wall; the hollow longitudinal walls on one side of the end-wall communicating with the gas passage and with the vertical flues at the top 20 of the latter and the hollow longitudinal walls on the other side of the end-wall communicating with the vertical flues at the bottom of the latter, and having peep-holes opening into the interior of the longitudinal walls adjacent to the horizontal gas passage in the end-wall.
15. In testimony whereof I hereunto affix my signature.

VICTOR C. DOERSCHUK.
